WILLIAM F. HENDRY, OF WESTCHESTER, NEW YORK, ASSIGNOR TO MANHATTAN ELECTRICAL SUPPLY COMPANY, INC., OF NEW YORK, N. Y., A CORPORATION OF MASSACHUSETTS

ELECTRIC SIGN AND CONTROLLING CIRCUITS THEREFOR

Application filed July 14, 1927. Serial No. 205,617.

This invention relates to electromechanically controlled optical systems and especially to methods and means for producing electrically, a pictorial representation for advertising or similar purposes.

An outstanding feature of the invention is concerned with a changeable light screen in combination with means for electromechanically producing on said screen any desired 10 picture or rapid succession of pictures.

Another feature pertains to a device comprising a bank of neon lamps and associated circuit controllers for variably lighting the lamps in the bank in rapid succession.

15 A still further feature relates to a changeable sign made up of a bank of neon lamps which may be illuminated in varying combinations under control of a non-pictorial record to produce the effects of a moving picture.

20 Another feature relates to a changeable sign comprising a multiplicity of electric lamps arranged in co-ordinate groups and commutator means for economically lighting any one or a combination of lamps in succession.

25 Another feature relates to a circuit controller mechanism for a changeable sign, which mechanism is adapted to be operated at comparatively high speeds without sparking or other deleterious effects on the commutator itself.

30 A still further feature resides in a multiple unit changeable sign employing neon lamps of the half wave type for the sign units, together with perforated circuit control bands operating in definite time relations with the current variations to reduce wear and deterioration of the control bands.

35 The invention also contemplates the novel organization of lamps, commutators and mechanical media records which go to make up an efficient "moving picture" sign.

40 Other features and advantages of the invention will become apparent after a consideration of the following detailed description and as pointed out in the appended claims.

45 Referring to the drawing, Fig. 1 shows one embodiment of the invention employing a changeable sign and comprising a plurality of

coordinately arranged half-wave neon lamps and associated circuit controllers.

Fig. 2 shows a modification of a commutator for controlling the circuits of the vertical rows of lamps.

Fig. 3 is a schematic representation of the relations between the lamp currents and the perforated base circuit controllers.

55 Referring to Fig. 1 of the drawing, there is shown a bank of lamps, each unit of which 60 operates on the principle disclosed in the W. F. Hendry application, Serial No. 180,788, filed April 4, 1927. As described in said application, these lamp units are adapted to be operated preferably by alternating current and are so designed that only one half of the wave of the alternating current passes through them. The purpose of employing lamps of this type will become apparent after a consideration of the following description.

65 For the purpose of securing simplicity in the drawing, the lamp bank is shown as made up of nine coordinately arranged rows of lamps. It is to be understood, however, that in practice a far greater number of lamps 70 may be employed, depending upon the desired detail in the picture to be formed on the lamp bank. For example, one form of lamp bank which permits of the optimum effects being produced comprises a bank 75 made up of 160 vertical rows of 200 lamps in each row. This arrangement therefore consists of 32,000 coordinately arranged lamp units. One method of forming on such a lamp bank an instantaneous image suitable 80 for moving pictures is to light each of the individual lamp units in succession and with such rapidity that due to the retentiveness 85 of vision a continuous visual impression is produced. When a single fixed image is to be produced this method of producing it may be employed. However, when rapidly successive images are to be produced on the lamp bank to give the effect of a moving picture, it is necessary that each of the successive images be completely produced on the lamp bank within 1/16th of a second in order 90 to give an observer the effect of continuity.

95 With lamp banks of the size above described, this method of individually lighting each 100

lamp is not practical for the reason that the commutator speeds necessary, are excessive. That is to say, with a bank of 32,000 lamps, in order to produce pleasing moving images, the commutating apparatus must be capable of closing the circuits of the 32,000 lamps in 1/16th of a second. To obviate this difficulty the present invention contemplates dividing the lamp bank into vertical groups, for example, the 160 vertical rows of lamps may be divided into 16 vertical groups with 10 vertical rows of lamps in each group. This arrangement is schematically represented in Fig. 1 by the groups $G_1, G_2, \dots, G_{16}$. For the sake of securing simplicity in the drawing and description only three vertical groups are shown and only three rows in each group. Similarly, only the first nine lamps in each vertical row are shown, it being understood, however, that each vertical row comprises 200 lamps.

From an inspection of Fig. 1, it will be seen that corresponding electrodes of the lamps in each vertical row are multiplied together, and that corresponding rows in each group are multiplied by means of the conductors 14, 15, 16, etc. Likewise, corresponding electrodes in each horizontal row are multiplied together, but corresponding horizontal rows in the several groups are not multiplied. It will be assumed that portions of the first two, and the last vertical groups of lamps are shown and that the individual vertical rows bear the numbers shown. With this arrangement any particular lamp may be illuminated, simply by completing a circuit through the corresponding multiplied horizontal and vertical conductors. For example, if it is desired to light lamp 7'-2 alone in vertical group G_1 , current is connected to conductors 7 and 15. If it is desired to light both lamps 7'-2 and 6'-2 simultaneously, current is connected to conductors 6, 7 and 15.

Associated with each of the groups $G_1, G_2, \dots, G_{16}$ is a lamp circuit controller $C_1, C_2, \dots, C_{16}$. Each controller comprises a perforated sheet which is carried by an associated roller 20, 21, 22, etc. These rollers are mounted in suitable bearings represented schematically by the numerals 23, 24, 25, etc. The perforated sheet records 17, 18, 19 are adapted to be unreeled from the rollers 20, 21, 22 on to the associated rollers 26, 27, 28 which are mounted for rotation in any well known manner and are adapted to be driven at a constant rate of speed from any convenient source of power. Devices of this character are well known in mechanically controlled instruments, such, for example, as pianolas and the like and further description thereof is deemed unnecessary. It will be noted, however, that all the controllers may be mechanically connected to operate in unison by a synchronized motor 35* as shown in Fig. 1 or may be ar-

ranged to operate in synchronism by electrical or other well known means in any desired manner. Each horizontal row of perforations in a record sheet corresponds, at any given instant, to a particular vertical row of lamps. For example, with the records in the position shown in Fig. 1 which will be assumed as the starting position, the horizontal row 29 in sheet 17 corresponds to vertical lamp row 1, horizontal row 30 corresponds to vertical row 2 and similarly for the succeeding horizontal rows in the sheet. It will be understood that each of the sheets 17, 18, etc. is perforated in advance in accordance with the design or picture to be produced on the lamp bank. Suitably mounted between the rollers of each controller is a metallic bar 32, 33, etc. over which the perforated record sheet is adapted to pass. Each controller is provided with a plurality of brushes equal in number to the number of lamps in each vertical row, and these brushes are conveniently mounted to contact with the bars 32, 33, etc. when corresponding perforations in the sheets 17 and 18 appear. In the form of lamp assumed there will be 200 of these brushes for each controller, each brush being connected to a corresponding horizontal row of lamps in the associated group as clearly shown in the drawing.

For the purpose of completing the circuits through the vertically multiplied electrodes in the proper sequence a controller C_v is provided which is similar in construction to the controllers $C_1, C_2, \dots, C_{16}$. However, since it is assumed that each of the groups $G_1, G_2, \dots, G_{16}$ comprises 10 vertical rows the controller C_v is provided with only ten brushes.

It will be assumed that it is desired to produce an instantaneous image on the screen S as represented by the crossed circles. Accordingly, with the records in the starting position, since lamps 5 and 6 in vertical row 1, lamps 2, 6, 8 and 9 in vertical row 11, and lamps 1, 2, 3, 4, 5, 7, 8 and 9 in vertical row 151, are all to be lighted, perforations will be found in registry with brushes 5 and 6 of controller C_1 , with brushes 2, 6, 8 and 9 of controller C_2 , and with brushes 1, 2, 3, 4, 5, 7, 8 and 9 of controller C_{16} . Likewise, since this is the first row of lamps in each vertical group to be lighted a perforation will be found in registry with brush 1 of controller C_v . Accordingly, circuits may be traced from one terminal of the source of current 35, bar 34, brushes 1, 2, 3, 4, 5, 7, 8 and 9 of controller C_{16} , corresponding terminals of lamps in vertical row 151, conductor 14, brush 1 of controller C_v , bar 36 to the other terminal of source 35. Similar circuits may be traced for lamps 2, 6, 8 and 9 in vertical row 11 through controller C_2 , and for lamps 5 and 6 in vertical row 1 through controller C_1 . These lamps remain lighted while the perforations are passing

beneath the controller brushes. Assuming the horizontal rows of perforations in the controllers are separated 1/8th of an inch apart from center to center, that the perforations are at least 1/16th of an inch in diameter, and assuming the speed of the sheets through the controllers to be at the rate of twenty inches per second, then the above traced circuits for the lamps in vertical rows 1, 11 and 151 will remain closed for approximately 1/160th of a second. During the next 1/160th of a second the brushes of the controllers are insulated from the associated contact bars by means of the record strips. At the beginning of the next interval of 1/160th of a second, the second row of perforations, for example, row 30 in controller C_1 and corresponding rows in the remaining controllers are brought into registry with the controller brushes. Accordingly, circuits may be traced through brushes 4, 6 and 7 of controller C_1 , terminals of the corresponding lamps in vertical row 2, conductor 15 and brush 2 of controller C_1 , returning to the current source 35. Similar circuits may be traced for lamps 1, 4, 5, 7, 8 and 9 in vertical row 12 through controller C_2 , and for lamps 1, 2, 3, 4, 5, 7, 8 and 9 of vertical row 152 through controller C_{16} . During the next time interval of 1/160th of a second the brushes are insulated from the contact bars and the paper records are advanced to bring the next rows of perforations into registry with the associated brushes to light the proper lamps in rows 3, 13 and 159. The desired lamps in the remaining vertical rows are lighted in a similar manner by the advancing of the associate controller strips. At the end of the tenth row, which is at the end of 1/160th of a second from the start, all the lamps in the 160 vertical rows will have thus been lighted and due to the retentiveness of vision of the eye an observer is unable to sense the intermittent lighting of the lamps since the entire image is produced in 1/16th of a second.

After a complete instantaneous image has thus been produced on the screen S corresponding to the first ten rows of perforation in each record sheet, the paper is unperforated for approximately the next $1/2$ inch, after which the first lines of perforations in each record corresponding to the next image are brought into registry with the controller brushes. If a moving image is to be reproduced, the arrangement of the perforations in the next ten rows of each strip will be slightly different from the preceding rows similarly to the succeeding "frames" of a motion picture film. One method for preparing the perforated records to control the reproduction of successive images will be described hereinafter.

Fig. 2 of the drawing shows a modified form of commutator which may be employed in place of the controller C . The conductors 14, 15 and 16 leading from the multiplied vertical rows instead of terminating in the brushes 1, 2, 3 of the controller C , are brought to the fixed contacts of a rotary commutator whose brush 38 is connected to one terminal of the source 35, the other terminal of the source being connected to the bar 34. The shaft on which brush 37 is mounted may be mechanically connected to the driving means for the controllers C^1 and C^2 — C^{16} or the brush 37 may be rotated in synchronism with the controllers by electrical or other suitable means.

While in the foregoing description the controller brushes are designed to bear upon the paper records, it will be seen that with the high speed of movement of the paper strips, the same will be subject to much wear due to the mechanical drag of the brushes on the paper surface and due particularly to the 80 sparking which occurs when the circuits through the brushes are made and broken. To avoid this excessive wear, the novel arrangement disclosed in Fig. 3 may be employed. As disclosed in Fig. 3 alternating 85 current of a frequency related in a definite manner to the speed of movement of the paper strips is employed. With strips of the form hereinabove described, namely, with perforations approximately 1/16th of an inch in size and spaced apart approximately 1/8th of an inch from center to center, and assuming that the paper travels at the rate of 20 inches per second, it will be seen that if 10 successive perforations register with a given brush that the current will be interrupted at 1/160th of a second intervals. If direct currents were used to light the lamps or if full-wave lamps are employed, these sudden 100 interruptions of the current will cause much 105 sparking. To obviate this, an alternating current of the frequency of the circuit interruptions is employed, that is to say with possible circuit interruptions at the rate of 160 per second, an alternating current of 110 160 cycles per second would be employed and the time relations between the current variations and the paper movements would be as shown in Fig. 3 wherein the rise and fall of the lamp current is plotted horizontally against time and the corresponding motion of the paper and the relation of the perforations and brushes are shown beneath. For 115 example, it will be assumed that the magnified cross section of the paper record P shown in Fig. 3 is in the starting position and that the paper is moved towards the right. While in Fig. 3 the full wave form of the alternating current is shown, it will be apparent that when half-wave lamps of the type disclosed in the application of W. F. Hendry Serial No. 180,788 filed April 4, 1927 are employed that the actual current will be 120 intermittent and unidirectional as represented 125 130

by the positive shaded portions of the current curve in Fig. 3. Accordingly as brush *b* approaches the first perforation *p* the current is at zero and gradually builds up while brush *b* is in registry with the perforation until a maximum is reached when the brush is approximately in the center of the perforation. Similarly when the opposite side of the perforation *p* approaches brush *b* the current gradually dies down to zero so that reliance is not placed upon the mechanical interruption of the circuit by the paper and all sparking is avoided. If desired, instead of relying on mechanical contact between the brush *b* and the strip *s* the brush *b* may be out of engagement with the paper surface so that as the current builds up and while the perforation is passing the brush a point is reached where current begins to flow between the brush and the strip, due to high voltage required to operate gas conductor lamps. However, due to the timed relations between the movement of the paper strip and the growth and decay of the current this sparking will occur substantially in the central portion of the perforation and will have no deleterious effects on the edges of the paper strip perforations.

While the specific apparatus is described hereinabove for accomplishing the movable image effect on a sign it is understood that the invention is of wider application. For example, while the sign may be employed very readily for the production of moving outline images, it will be apparent that other forms of images may be reproduced and that various shadings may be simulated by the lighting of the lamps in the proper groups or clusters to give an effect similar to the "half tone" effect in photography. It is also understood that different colored lamps may be employed at various points throughout the bank to give novel effects as desired.

One method of preparing the record bands to incorporate a record therein for the purpose of producing shading or half-tone effects on the sign is as follows:

A magnified photographic print of the image desired to be reproduced on the lamp bank is first prepared by any of the well known half-tone printing processes. A mesh screen having perforations corresponding in number and arrangement to the number and arrangement of the lamps in the bank is placed over the half-tone. This screen has the horizontal rows of perforations and the vertical rows of perforations coordinate-ly numbered similarly to the numbering of the lamps in the bank and spaces in the paper strip. It is obvious, therefore, that the picture on being inspected through the screen may be analyzed in accordance with the numbering of the perforations. The record bands may then be perforated in any well known manner to correspond to the analyza-

tion of the picture in accordance with the vertical and horizontal rows. If a single half-tone image is to be reproduced one analyzation alone is necessary and the record in the commutator bands may be repeated indefinitely or a single continuous band may be employed. When moving images are to be reproduced the analyzation of magnified prints of successive images is necessary in order that the commutator bands may be correspondingly perforated to control the successive illumination of the desired lamps in the lamp bank.

While in the foregoing description alternating current is assumed as the source of energy for illumination of the lamps and while alternating current lamps are employed, it is understood that any form of interrupted direct current and corresponding direct current lamps may be employed. The broad idea being the synchronizing of the current variations with the movement of the record bands. Therefore, so-called "full-wave" lamps may be employed and rectified alternating current may be used, or direct current lamps operated by regularly interrupted current would come within the scope of the invention.

What I claim is:

1. In combination, an advertising sign comprising a bank of lamps including means to pass only currents of one polarity, a source of alternating current, a circuit controller record of the lamps in said bank to be lighted, and means for moving said controller at such a rate with respect to the frequency of said alternating current that said controller initially closes and initially opens the circuits to said lamps during the portions of the alternating cycle when the lamps pass a minimum of current.

2. In an advertising sign, a plurality of co-ordinately arranged electric lamps, said lamps being arranged in vertical groups, means for connecting corresponding terminals of all the lamps in each corresponding vertical row of each group, means for connecting together corresponding terminals of all the lamps in each horizontal row of a group, a separate perforated sheet circuit controller associated with and controlling each of the second mentioned connecting means, a perforated sheet circuit controller common to all of said first means, and means for operating all of said controllers in synchronism to selectively light any lamp or group of lamps simultaneously in each group for the purpose of producing movable image effects.

In testimony whereof, I have signed my name to this specification this 13 day of July, 1927.

WILLIAM F. HENDRY.
